VACUUM CLEANER BRUSH BEARING

Filed Jan. 3, 1928

Inventor:
James M. Darst,
His Attorney.

UNITED STATES PATENT OFFICE

JAMES M. DARST, OF EAST CLEVELAND, OHIO, ASSIGNOR TO ELECTRIC VACUUM CLEANER COMPANY, INC., OF CLEVELAND, OHIO, A CORPORATION OF NEW YORK

VACUUM-CLEANER-BRUSH BEARING

Application filed January 3, 1928. Serial No. 244,071.

The present invention relates to a vacuum cleaner brush bearing and has for its object to provide an improved bearing of this character which is thoroughly sealed and protected from lint, threads and dust-laden air to which it is subjected in use, which is at the same time readily demountable in the field for cleaning and inspection, and which permits the brush assembly to be removed and 10 placed without dismantling the bearing.

For a consideration of what is believed to be novel and my invention, attention is directed to the accompanying drawing, the following description taken in connection with the 15 drawing, and the appended claim.

In the drawing, Fig. 1 is a side view of a vacuum cleaner having a rotary brush with which the bearing of the present invention is adapted to be used; Fig. 2 is an enlarged view, 20 partly in cross section, showing a bearing embodying the invention mounted in the nozzle of the vacuum cleaner of Fig. 1, one end of the brush and one bearing being shown, and Fig. 3 is a further enlarged view in cross section showing the interior construction of said bearing.

Referring to Fig. 1, 5 is the casing of a vacuum cleaner having a forwardly extending floor nozzle 6 through which dust and 30 other matter are drawn by a suction fan 7 and delivered through the casing to a dust bag 8. The nozzle is supported on side rollers or casters 9 and is fitted with a rotary floor brush indicated at 10. The brush is provided with a 35 pulley 11 which is driven through a belt 12 by a driving pulley 13. The driving pulley and fan are mounted on a common shaft 14 which is driven directly by an electric motor 15, the armature of which is indicated at 16. The cleaner is moved over the surface to be 40 cleaned by a suitable handle 17 and is supported at the rear by a caster or wheel 18.

The above-described vacuum cleaner represents any vacuum cleaner having a rotary brush to which bearings embodying the invention may be applied. In the present example the brush is journaled within the nozzle according to the usual practice in bearings supported by the nozzle side walls as shown 50 more fully in Fig. 2.

Referring to Fig. 2, 19 is a tube which carries the centrally mounted driving pulley 11 and the brush proper 10 comprising the usual rows of hair tufts inserted in the walls of the tube. The tube, brush proper and pulley 55 may be conveniently termed the brush and represents any rotary brush for a vacuum cleaner. The brush is mounted at each end in bearings, the exterior housing of one of which is shown at 20 and the latter is in turn 60 carried in a fixed holder 21 of suitable construction secured to the side wall of nozzle 6. In the present example it is secured to a boss 22 integral with the nozzle wall. The particular holding means for the bearings does not 65 concern the present invention. However, it is arranged preferably to permit the easy removal from and insertion in the nozzle of the brush with its bearings.

Referring now to Fig. 3, the bearing housing 20 is a single-piece or unitary, cylindrical, cup-shaped member into which a suitable bearing, such as a ball bearing 23 is pressed, the outer race 24 of the bearing being thereby held by the housing. The housing is adapted 70 to be gripped and held on its exterior about the bearing and is there provided with a pressed exterior projection 25 which prevents it from rotating in the holding means 75.

The inner race 26 of the bearing is free to 80 rotate and receives the shouldered end of an axially extending hollow stud 27 connected with the brush. The stud is slidably removable from the inner race and is held therein by a finely pitched screw 28 which engages 85 corresponding threads 29 in the bore 30 of the stud and draws the shouldered end of the stud into a seated position within and against the inner race. A lock washer 31 beneath 90 the head of the screw and the fine pitch of the screw prevents the stud from loosening from the bearing in operation.

The bearing is lubricated when necessary and the screw 28 is readily accessible, through 95 a bossed central opening 32 in the end wall of the housing adjacent the bearing and directly in line with the screw. The opening is provided with a suitable closure means, such as a screw cap 33. The bearing is thus protected from dust on one side by the closed end of 100

the housing. On the opposite side it is protected by a cup-shaped packing washer 34 which surrounds the stud and seats adjacent to the outer race within the housing. The washer carries a ring packing 35 of suitable material and a retaining washer 36 for the packing. The packing contacts with the stud and packs it against dust and other foreign matter which may tend to enter the bearing.

10 The brush stud 27 is connected with the brush by a flanged or grooved head 37 which is integral with the stud and which is pressed onto the end of the brush tube. The brush, grooved head, stud and inner race are thus connected and are rotatable together about a common axis, while the housing, outer race and packing means remain stationary. The housing is enlarged at its outer end to receive the grooved head fully within it and is of such internal diameter about the head that only a close running clearance space 38-38 is provided between it and the head. This space, together with an annular chamber 39 formed by the groove in the head provide a labyrinth packing between the dust-laden air within the nozzle and the inner packing means 34 and 35. The head for the brush tube is also protected from thread winding 20 by the housing which extends over it, that is overhangs the flange 40.

25 The above-described bearing structure may be considered to comprise a brush assembly which includes the brush or brush tube 19 with the heads mounted thereon, and the bearing assembly which includes the housing 20, bearing 23, and packing means, together with screw 28 and washer 31. With the construction shown the brush assembly may be 30 removed from the bearing assembly by simply removing cap 33 and unscrewing screw 28. The brush assembly is then withdrawn axially as indicated by the dotted outline 41 leaving the bearing assembly in readiness to 35 receive a new brush assembly without disturbing the bearing arrangement.

40 This construction thus makes field servicing of the bearing and brush structure very simple and easy since the brush when worn out is thus easily removed and replaced by a new one and the bearing is easily relubricated through the opening provided by removable cap 33. This results in a saving to the user 45 since the brush replacement involves only the cost of the brush and is quickly accomplished.

45 The easy removal of the brush assembly from the bearing also facilitates occasional cleaning of the bearing and brush. The construction has the advantage that the support for the bearing may be located directly about the bearing, thus eliminating vibration and wear ordinarily occasioned by an overhung 50 construction in which the bearing is supported

axially at a distance from the bearing surfaces.

What I claim as new and desire to secure by Letters Patent of the United States is:-

55 In a bearing structure for vacuum cleaner brushes and the like, the combination with a rotary member, of an end bearing structure therefor comprising a head mounted on the end of said member, an axially extending stud carried by the head, said stud having a 60 shouldered end, a ball bearing having an outer race and an inner race, in which inner race the shouldered end of the stud is seated, means carried by the stud for engaging the inner race to hold the stud in said seated position, 65 said means being releasable to permit the stud to be withdrawn from the bearing, a cylindrical cup-shaped housing having at one end an enlarged portion which surrounds the head with a close running clearance, said head being 70 provided with an annular groove which forms a labyrinth packing with the enlarged portion of the housing, at the opposite end of said housing enclosing the bearing, and a removable closure means for said opposite 75 end of the casing, said closure means being axially in line with the holding means and adjacent the bearing, whereby by removing 80 said closure means, said holding means may be removed and the bearing and outer member of the packing removed as a unit from the 85 stud.

85 In witness whereof, I have hereunto set my hand this 24th day of December, 1927.
